BENT WIRE PUZZLE

Albert J. Gore, Washington, D. C., assignor of
forty-five per cent to Philip Larner Gore

Application March 18, 1946, Serial No. 655,196

5 Claims. (Cl. 273—158)

1

My invention consists in a new and useful improvement in puzzles of that type which comprises wire members which may be interengaged to present the problem of their disengagement as the solution of the puzzle. In devices of this kind, it is quite common to provide two members for interengagement, each of which is formed into a plurality of convolutions of a single wire, and one member has its ends united while the other member is so fabricated as to provide a gap between the ends of the wire of which it is composed, so that one member is a closed element and the other member is an open element in the combination.

The peculiarly novel features of my improved puzzle are the relative proportions of the closed and open members, the peculiar relation and character of the convolutions at their ends, and the form and relative positions of the ends of the open member.

While I have illustrated in the drawings and have hereinafter fully described one specific embodiment of my invention, it is to be distinctly understood that I do not consider my invention limited to said embodiment but refer for its scope and understanding to the following description and claims appended thereto:

In the drawings, wherein the same reference characters represent the same parts in the several views:

Fig. 1 is a front elevation and

Fig. 2 is a side elevation of the closed member;

Fig. 3 is a front elevation and

Fig. 4 is a side elevation of the open member;

Fig. 5 is a front view of the closed member, as in Fig. 1, and a side view of the open member, as in Fig. 4, the members being in one interengaged position;

Fig. 6 is a similar view of the same members in a second interengaged position;

Fig. 7 is a similar view of the same members in a third interengaged position;

Fig. 8 is a side elevation of the open member and a cornerwise view of the closed member in a fourth interengaged position; and

Fig. 9 is a view similar to Figs. 5, 6 and 7 of the members in a fifth interengaged position.

As illustrated in the drawings, my improved device consists in a closed member A and an open member B, each one formed of a single wire, circular in cross-section, the gauge of the two wires being the same. As shown in Figs. 1 and 2, the member A has straight portions 1 and 2 joined at their upper ends by the spiral portion 3 comprising three semi-circular parts 3—a, 3—b, 55

2

and 3—c, whereof 3—a and 3—c, which are spaced apart to form a throat T somewhat wider than the gauge of the wire (Fig. 2) form the upper half, and 3—b forms the lower half of the circle 3—x (Fig. 1). The portions 1 and 2 diverge and merge at their lower ends into semi-circular parts 1—a and 2—a respectively. It will be noted (Fig. 1) that while the parts 1—a and 2—a have radii of the same length, they are not concentric due to the divergence of the portions 1 and 2, the centers of the parts 1—a and 2—a being symmetrically spaced on either side of the vertical axis of the member A. It will also be noted (Fig. 2) that the portions 1 and 2 diverge also in the plane at right angles to the plane of Fig. 1. As clearly shown in Fig. 2, the parts 1—a and 2—a are disposed in intersecting vertical planes so that the tongues 1—b and 2—b, which extend upwardly from the parts 1—a and 2—a respectively, 20 somewhat overlap the lower ends of the portions 1 and 2. It will be noted that the relation of the tongues 1—b and 2—b to the portions 1 and 2 is such that in the plane of Fig. 1 the joints formed by 1, 2—b and 2, 1—b are of a thickness equal to twice the gauge of the wire, and in the plane of Fig. 2 the thickness of the joints is only about 1½ the gauge. It will also be noted that at the point where the parts 1—a and 2—a cross the vertical axis of the member A the vertical diameter of the joint is that of the gauge. The contacting surfaces of the portions 1 and 2, parts 1—a and 2—a, and tongues 1—b and 2—b are permanently united as by solder or any other suitable medium, thus making the member A the closed member of the combination.

As shown in Figs. 3 and 4, the member B has the straight portions 11 and 12 joined at their upper ends by the spiral portion 13 comprising three parts 13—a, 13—b and 13—c, whereof 13—a and 13—c, which are spaced apart to form a throat T' of substantially the same width as the throat T of the member A, form the upper half and part 13—b forms the lower half of an approximately circular coil 13—x, the diameter of which is equal to the diameter of the circle 3—x formed by the spiral portion 3 at the upper end of member A. The portions 11 and 12 are approximately parallel and merge at their lower ends into the co-axial similarly curved parts 11—a and 12—a respectively, their centers lying in the vertical axis of the member B. It will be noted (Fig. 4) that the portions 11 and 12 diverge in the plane at right angles to the plane of Fig. 3. As clearly shown in Fig. 4, the parts 11—a and 12—a are so disposed that their longitudinal axes lie

in the divergent planes of the longitudinal axes of the portions 11 and 12 respectively, thereby forming the throat T' which, due to the divergence of the portions 11 and 12 is approximately twice the width of the throat T', thus making the member B the open member of the combination.

From the foregoing description of the structure of the members A and B, it will be seen that the members can be interengaged, moved into and out of a variety of relative positions and disengaged by passing their straight and curved portions through the throats T, T' and T''. There will now be described a method by which the members may be interengaged, brought into several relative positions shown in Figs. 5, 6, 7, 8 and 9, and then disengaged. In this method, the members are interengaged by the introduction of the open member B into the closed member A at the lower end of the member A (Fig. 1) and are disengaged by removal of member B from member A at the upper end of member A (Fig. 1). It is obvious that the interengagement, movement to the illustrated positions and disengagement can be effected reversely, viz. interengagement at the upper end and disengagement at the lower end of member A by effecting the steps of the method inversely.

Hold member A vertical in position shown in Fig. 1. Hold member B horizontal. Pass part 11a over and part 12-a under parts 1-a and 2-a at the vertical axis of member A, 1-a and 2-a passing through throat T' of member B. Pass portion 1 through throat T''. Swing member B downwardly into vertical position, parts 1-a and 2-a being passed through ring 13-x, the members being interengaged as shown in Fig. 5.

Raise member B toward left, portion 1 passing through ring 13-x. Move parts 13-a and 13-c through throat T of member A, bringing them into ring 3-x, and member B into vertical position, the members A and B being then interengaged as shown in Fig. 6.

Swing member A slightly to pass portion 1 through throat T' of member B. Move member B upwardly to left until it is horizontal. Pass part 13-b through throat T of member A. Pass part 3-b through throat T' of member B. Move member B upwardly to right until it is vertical, the members A and B being then interengaged as shown in Fig. 7.

The above-described movements whereby the members A and B are interengaged as shown in Figs. 5, 6 and 7 are successive steps in the method of interengaging them at the bottom of member A and disengaging them at the top of member A. I will now describe a movement whereby the members A and B are brought from their positions of interengagement shown in Fig. 7 to interengagement shown in Fig. 8. This movement is not a step toward disengagement of the members A and B, and is described and illustrated to show one of the numerous positions of interengagement which present the problem of disengaging the members A and B.

Move member B upwardly through 180°, portion 11 passing between portion 1 and part 3-b of member A, part 13-a wedging upwardly between parts 3-a and 3-c of member A, and part 13-a passing through ring 13-x, about parts 3-a and 3-c, the members A and B then being interengaged as shown in Fig. 8.

From the foregoing, it is obvious that by reversing the last described movement the members

A and B are returned to their positions as shown in Fig. 7.

5 Swing member B slightly to pass portion 1 through throat T'', and move member B upwardly through 180°, the members A and B then being interengaged as shown in Fig. 9.

10 Move member A to right through 90°. Pass parts 3-a and 3-c through throat T', along portion 11, through throat T'' and past part 11-a to disengage members A and B.

Having described my invention, what I claim is:

15 1. A puzzle comprising a pair of link members having loops at both ends each of which consists of a single piece of wire, the two pieces of wire being stiff enough to resist bending, one of said members having a spiral portion and two side portions forming extensions of the spiral portion, said side portions being looped and united at their ends, the other of said members having a spiral portion and two side portions forming extensions of said last mentioned spiral portion, and symmetrical arcuate extensions from said last mentioned side portions, respectively, 20 forming loops disposed in the planes of the last mentioned side portions so as to provide a throat between them.

25 2. A puzzle comprising a pair of link members having loops at both ends each of which consists of a single piece of stiff wire, the two pieces of wire being of approximately the same gauge, one of said members having a spiral portion and two side portions forming extensions of the spiral portion and united at their ends, the other of said members having a spiral portion and two side portions forming extensions of said last mentioned spiral portion, and symmetrical mutually arcuate extensions from said last mentioned side portions, respectively, forming loops disposed in the planes of the last mentioned side portions transverse to the axis of said spiral portion, the first member being provided by its spiral portion with a throat at one end, and the second member being provided by its spiral portion with a throat at one end, and by said arcuate extensions with a throat at its other end between said loops, said throats of said second member having a common axis of symmetry normal to the axis of said spiral portion of said second member, and each of said throats having a width greater than the said gauge.

30 3. A puzzle comprising a pair of link members, each of which consists of a single piece of stiff wire, one of said members having a spiral portion defining a transverse bore therethrough, two side portions forming extensions of the spiral portion, and arcuate extensions from the side portions, respectively, overlapping and united to form a closed figure, the other of said members having a spiral portion defining a transverse bore therethrough, the width of said bore being equal to the width of the bore of the first member, and its length on its major axis being no less than its width, two side portions forming extensions of said last mentioned spiral portion, and symmetrical arcuate extensions from said last mentioned side portions, respectively, forming loops disposed in the planes of said last mentioned side portions, so as to provide a throat between them permitting passage of said closed member through said throat in certain positions only.

35 4. A puzzle comprising a pair of link members, each of which consists of a single piece of stiff wire, the two pieces of wire being of approxi-

mately the same gauge, one of said members having at one end a spiral portion defining a bore therethrough, two straight portions extending divergently from the spiral portion, and convergent arcuate extensions from the straight portions, respectively, overlapping and united by a suitable means, the other of said members having at one end a spiral portion defining a bore therethrough, two straight portions extending divergently from said last mentioned spiral portion, and symmetrical arcuate extensions from said last mentioned straight portions forming loops disposed in the divergent planes of said last mentioned straight portions respectively, the first member being provided by its spiral portion with a throat at one end, and the second member being provided by its spiral portion with a throat at one end, and by its symmetrical extensions with a throat at its other end between said loops, said throats of said second member having a common axis of symmetry normal to the axis of said spiral portion of said second member, and each of said throats having a width greater than the said gauge.

5. A puzzle comprising a pair of link members, each of which consists of a single piece of wire, the two pieces of wire being of approximately the same gauge, one of said members having a spiral portion comprising three successive 180° bends, the middle bend forming one part and the lateral bends forming the other part of a closed figure, and the lateral bends being relatively spaced apart to form a throat therebetween which is wider than said gauge, two side

portions forming extensions of the spiral portion, and arcuate extensions from the side portions mutually overlapping and united by suitable means, the second of said members having a spiral portion comprising three successive 180° bends, the middle bend forming one part and the lateral bends forming the other part of a closed figure having a diameter substantially equal to the diameter of the closed figure formed by the spiral portion of the first member, the lateral bends of said second member being relatively spaced apart to form a throat therebetween which is wider than said gauge, two side portions diverging from said last mentioned spiral portion, and symmetrical arcuate extensions extending from said last mentioned side portions and forming loops disposed in their divergent planes, respectively, said loop extensions being relatively spaced apart to provide a throat wider than said gauge, the length of said first member being substantially greater than the length of said second member, whereby said second member can be passed transversely through said first member when said spiral portions thereof interengage with each other.
